[57] **CLAIM**

The ornamental design for an oral examination tongue depressor, as shown and described.

DESCRIPTION

FIG. 1 is a top view of an oral examination tongue depressor showing our new design;

FIG. 2 is a bottom view thereof;

FIG. 3 is a side elevational view, the view from the opposite side being a mirror image thereof;

FIG. 4 is a left end elevational thereof;

FIG. 5 is a right end elevational view thereof;

FIG. 6 is an enlarged fragmentary bottom plan view of the left end as shown in FIG. 2;

FIG. 7 is an enlarged fragmentary bottom plan view of the right end as shown in FIG. 2;

FIG. 8 is an enlarged fragmentary cross-sectional view thereof, taken along the line 8—8 of FIG. 7; and,

FIG. 9 is a cross-sectional view thereof, taken along the line 9—9 of FIG. 3.
